UNITED STATES PATENT OFFICE.

E. MATHERS AND W. D. SIEGFRIED, OF MORGANTOWN, VIRGINIA.

APPARATUS FOR FEEDING PAPER TO HAND PRINTING-PRESSES.

Specification of Letters Patent No. 12,634, dated April 3, 1855.

To all whom it may concern:

Be it known that we, EBENEZER MATHERS and WILLIAM D. SIEGFRIED, of the town of Morgantown, county of Monongalia, and

5 State of Virginia, have invented a new and useful Improvement in Feeding Hand Printing-Presses; and we do hereby declare that the following is a full, clear, and exact description of the construction and operation 10 of the same, reference being had to the annexed drawings, making a part of this specification, in which—

Figure 1 is a longitudinal elevation. Fig. 2 a top view and Fig. 3 a section, with letters of reference marked thereon.

A, A, Fig. 1, a common hand printing press, of which B is the platen and C, is the carriage. a, a, feed-board, placed upon a frame and inclined say at an angle of 26 degrees. The frame and feed board rest upon sliders i, i, on each side of the carriage, which sliders are supported by bars passing under and bolted to the ribs of the press and bent up at right angles at each end. b, b, 20 a clamp hinged to the front of the carriage C, its position is either resting on the chase, or raised up as seen at Fig. 1. d, d, guide rods, attached at one end to the platen, at the other end resting in holes in the feed 25 board, these rods with all their appendages may be raised up and rested against the top of the press, thus placing them out of the way, when necessary to adjust the form. c, c, a sliding clamp, moving freely upon the 30 guide rods d, and moved by the cords attached to the cam levers f, f, which are fixed to the front of the carriage by arms. These cords pass from f, under the pulleys e, e, on the platen, from thence to the clamp, to 35 which they are fastened, other cords attached to the back edge of the clamp, passing over the pulleys e, e, at the back end of the rods, to the weight j. This clamp has a single pair of fingers extending backward, 40 with a spring between them, to close the clamp, and spring catches y, y, arranged to keep the clamp open when necessary. g, g, 45 a stationary bar fixed to the guide rods and supporting a device for opening the clamp c. At k, Fig. 1, is seen a device for opening the clamp, b, by striking the catches r, r, when the carriage is run in.

l, Fig. 1, is a device for operating the cam levers, f, f, in order to give an additional pull to the clamp c, when the carriage is 55 run in.

The mode of operation is as follows: Suppose the guide rods raised up and resting against the top of the press, the frame with feed board and other appendages, slid back 60 on the sliders clear of the form, the paper must now be placed on the board and the inking apparatus properly adjusted. The frame is then slid forward until it is in the position represented in Fig. 1. The guide 65 rods, with the clamp c, weights cords &c. is then lowered into their place and adjusted. The pressman then feeds the top sheet into the clamp b, and by a slight pressure on the upper jaw the clamp is latched by the spring 70 catches r, r, and thus clamps the front end of the sheet, he then runs in the form and makes the impression, the clamp c, has followed the sheet, until it arrived at the edge of the platen, when by the additional pull 75 given by the movement of the cam levers striking against l, the jaws pass beyond the edge of the sheet, at the same instant the teeth on the edge of the platen marked x, x, 80 striking the catches y, y, sets the spring free 80 and closes the clamp on the margin of the sheet, the pressman now runs back the carriage, bringing the printed sheet fast in the clamp c, until it arrives at g, when it is 85 pressed open, the sheet dropped and the catches y, y, hooked at the same moment. The clamp b carrying the front end of the sheet, had been opened by the fingers k, 90 striking the spring catches r, r, when the form was run in, and thus returns open, ready to receive another sheet. When it arrives at the point of the frame s, it is raised up until it reaches the edge of the feed board, against which it rests, when the carriage starts on its way inward, the clamp 95 sinks down on the chase, bringing the sheet to its proper place on the form.

The platen must be fitted with a wooden frame on which the necessary cloth and blankets may be stretched to form a tympan. 100

When the carriage is run out, the cam levers are made to assume the position as seen in the dotted lines at f, Fig. 1, by means of a check cord attached to their lower end, and

some convenient point say *l*, at the other end of the cord, the cams retain this position until the carriage is again run in, and thus allow the clamp *c* to follow behind the sheet 5 till the proper time to seize it.

The form is inked by the motion of carriage operating the rollers, as seen in Fig. 3, by means of a rack and pinion, but as this makes no part of our present claim, an exact description may not be necessary. 10

We have thus described the construction and operation of our improvement, its advantages are 1st a saving of at least one-half the labor required to work a common 15 hand press, in the present mode. 2 securing perfect register by suitable guages on the feed board and clamp *b*. 3 the inking will

be more uniform than it can be done by hand. 4th it may be attached to any or all of the hand presses now in use, thus 20 doubling their efficiency.

What we claim and desire to secure by Letters Patent is—

The feeding hand presses automatically, by means of the operation of the clamps, 25 guide rods, cords, weights, pulleys, catches, and springs, arranged in the manner and for the purposes as above set forth substantially.

EBENEZER MATHERS.
WILLIAM D. SIEGFRIED.
